CLAIM

The ornamental design for a coffeemaker water dispenser, as shown and described.

DESCRIPTION

FIG. 1 is a perspective view of a coffeemaker water dispenser showing my new design;

FIG. 2 is a side elevational view thereof, the other side being a mirror image;

FIG. 3 is a front elevational view therof;

FIG. 4 is a top plan view thereof; and

FIG. 5 is a sectional view taken along lines 5—5 of FIG. 2. The back is substantially plain and unornamented.

Fig. 1.

Fig. 2.

Fig. 3.

Fig. 4.
